Primary Examiner — Mary Ann Calabrese(74) *Attorney, Agent, or Firm* — Lane Powell PC(57) **CLAIM**

The ornamental design for a display screen with color graphical user interface, as shown and described.

DESCRIPTION

The patent or application file contains at least one drawing executed in color. Copies of this patent or patent application with color drawings(s) will be provided by the Office upon request and payment of the necessary fee.

The FIGURE is a front view of a display screen with graphical user interface showing my new design.

The broken line showing of the display screen is for environmental purposes only and forms no part of the claimed design.
